(57) **CLAIM**

The ornamental design for a golf training device, as shown and described.

DESCRIPTION

The golf training device is used by a golfer with a putter to assist in perfecting golf putting strokes.

FIG. 1 is a side view of the golf training device showing my design.

FIG. 2 is an opposite side view thereof;

FIG. 3 is a rear view thereof;

FIG. 4 is a front view thereof;

FIG. 5 is a bottom view thereof; and,

FIG. 6 is a top view thereof.

The broken line showing is included for the purpose of illustrating and forms no part of the claimed design.
